UNITED STATES PATENT OFFICE.

WILLIAM F. GROENE, OF CINCINNATI, OHIO, ASSIGNOR TO THE R. K. LE BLOND MACHINE TOOL COMPANY, OF CINCINNATI, OHIO, A CORPORATION OF DELAWARE.

TAPER ATTACHMENT FOR LATHES.

Application filed June 8, 1921. Serial No. 476,037.

To all whom it may concern:

Be it known that I, WILLIAM F. GROENE, a citizen of the United States, residing at Cincinnati, county of Hamilton, and State 5 of Ohio, have invented an Improvement in Taper Attachments for Lathes, of which the following description, in connection with the accompanying drawings, is a specification, like characters on the drawings representing

10 like parts.

This invention relates to taper attachment for lathes whereby, as the lathe tool is moved longitudinally of the lathe, it will also be moved transversely of the lathe at

15 a speed bearing a predetermined relation to the movement longitudinally of the lathe.

Two types of taper attachments for lathes are now well known; in one type the taper guide rail is supported by the lathe carriage, 20 and in the other type the taper guide rail is supported from the lathe bed by means of a bed bracket. The present invention relates more particularly to the latter type, although 25 various features of the present invention are well adapted for either type of taper attachment.

In taper attachments for lathes, it is customary to provide a taper guide rail having a sliding shoe which is caused to slide along 30 the taper rail during the use of the taper attachment, but the shoe usually fits tightly upon the taper rail to prevent play from occurring therebetween, and as a result, considerable force is often required to move the. 35 shoe along the rail, particularly if the parts are not well lubricated.

An important feature of the present invention therefore, consists in a taper attachment of the type above indicated which is 40 so constructed that the cross feed screw is entirely relieved from lateral bending forces, and from longitudinal stresses throughout the use of the taper mechanism.

Another feature of the invention consists 45 in so constructing the taper attachment that the cutting tool may be easily and quickly placed under its control, and released therefrom.

The above and other novel features of the 50 invention will appear more fully from the following description and the drawings.

The accompanying drawings illustrate a good, practical form of the invention, the

details of which may be modified within the true scope thereof, as defined by the claims. 55

In the drawings:—

Figure 1 is a vertical transverse sectional view taken through the lathe bed and its carriage.

Fig. 2 is an enlarged plan view of the taper attachment and a portion of the carriage, 60 showing the taper attachment in use.

Fig. 3 is a view similar to Fig. 2 but showing the taper attachment out of operation; 65

Fig. 4 is a rear elevation of the parts shown in Fig. 3.

In the drawings, 10 designates the lathe bed having the carriage 11 slidably mounted thereupon; and mounted upon the carriage 70 is the cross-slide 12 which supports the tool-carrying mechanism 13. The construction of these parts forms no part of the present invention, and they may be of the usual or any preferred embodiment. 75

In the present embodiment of the invention, the cross-feed screw 14 is operatively connected to the cross-slide 12 by suitable means such as a nut 15 secured to the cross-slide by a shank 16 and nut 17, and the rear 80 end of the screw 14 is rotatably secured to a relatively long sleeve 18. In the present instance the rear portion of the screw 14 extends through the sleeve 18 and is journaled 85 therein, thrust bearings 19 and 20 being provided upon the screw at the ends of the sleeve to prevent relative longitudinal movement between the sleeve and screw.

The sleeve 18 is supported by the lathe carriage 11 for sliding movement transversely of the lathe, and to this end, in the embodiment shown, one end portion of the sleeve 18 is slidably received in a guide-way 21 while the opposite end portion of the sleeve is slidably received in a guide-way 22 95 of the out-bracket 23. The bracket 23 may be given the construction shown (see Fig. 2) and may be rigidly secured to the carriage 11 by suitable means such as bolts 24. The arrangement just described is such that the sleeve 18 is permitted to slide in the direction of its length, but is strongly supported against displacement relatively to the carriage in a direction transversely to the length of the sleeve. 100

As stated, the present invention relates 105

more particularly to the type of taper attachment in which the taper guide rail is supported from the lathe bed. Any suitable bed bracket, such as indicated by 25 may be 5 provided to support the taper rail, and this bracket may be adjustably secured to the lathe bed 10 by the bar 26 received in the dove-tailed groove 27 of the lathe bed, and the bar 26 may be secured to the bed bracket 10 by bolts 28. The upwardly extending portion of the bracket 25 has a face plate 29 upon which the taper rail 30 is pivotally mounted by the pivot pin 31. Upon the taper rail 30 is slidably mounted a shoe 32 15 adapted to be secured to the sleeve 18 in a manner to be described.

The taper rail 30 is adapted to be adjusted angularly about the pivot pin 31, and various means may be provided for effecting this adjustment. The means shown 20 consists of a threaded bolt 33 having threaded engagement with a downwardly extending bolt or stud 34. The face plate 29 is provided with a curved slot 35 to clear this 25 bolt and a nut 36 upon the lower end of the bolt serves to clamp the taper rail to the face plate in the desired position. The adjusting bolt 33 has a shoulder 37 mounted in a socket in the face plate which serves 30 to hold the bolt from moving in the direction of its length, and this bolt may have a head 38 for rotating the bolt to effect adjustment of the taper rail.

In the embodiment of the invention disclosed, it is desirable to provide means for securing the sleeve 18 to the sliding shoe 32 during the use of the taper attachment, and to release the sleeve from the shoe and to 35 secure the sleeve against movement relatively to the carriage during the normal operation of the lathe. This may be satisfactorily accomplished by providing a bolt 39 40 insertable in a hole 40 within the sleeve and having threaded engagement with a threaded 45 socket 41 in the shoe to operatively connect the sleeve and shoe. When it is no longer desired to use the taper attachment, the bolt 39 is removed and is inserted in a 50 hole 42 extending transversely through the out-bracket 23. In this position the threaded end of the bolt 39 engages a threaded 55 socket 43 in an enlargement 44 upon the sleeve 18 and serves firmly to clamp a face 45 of this enlargement against the inner face of the bracket 23.

When the sleeve 18 is secured by the bolt 39 to the shoe, and the carriage 11 is moved along the lathe bed, the shoe will be moved along the taper rail 30 and will 60 impart movement to the sleeve 18, cross-feed screw 14, and through the latter to the cross-slide 12 in a direction transversely of the lathe. The connection between the sleeve and shoe serves to slide the shoe along the 65 taper rail, but since the sleeve 18 is strongly

supported by the guide-ways 21 and 22, it is well adapted to withstand the lateral forces to which it may be submitted, and the end of the cross-feed screw within the sleeve is relieved from all lateral bending forces. 70

The forward end 46 of the cross feed screw is slidably received in a sleeve 47 to which it is keyed, and this sleeve may be rotated by a handle 48 to rotate the cross feed screw, in this manner the movement of 75 the screw in a direction of its axis during the use of the taper attachment is taken care of.

It is desirable to provide means for rigidly connecting the cross-feed slide 12 to 80 the sleeve 18 when the taper attachment is in use and after the screw 14 has been rotated to adjust the cross-slide. To this end, in the embodiment shown, a slotted bar 49 is provided, one end of which is firmly secured to the cross-slide 12 by a pin 50 and bolt 51. The slot 52 of the bar is adapted to 85 slidably receive the clamping bolt 53 having threaded engagement with the sleeve 18. The arrangement is such that the bar 49 may 90 be firmly clamped against the upper face of the sleeve by tightening the bolt 53 to force the clamp 54 against the upper face of the bar.

From the foregoing description when read 95 in connection with the drawings, it will be seen that the cross-feed screw is relieved from all lateral bending forces throughout the use of the taper attachment, and that by tightening the clamping nut 53, a rigid 100 connection is formed between the cross-slide and sleeve which relieves the cross-feed screw from longitudinal stresses. It will also be apparent that the taper attachment may be easily and quickly brought into 105 operation, and the parts may again be restored to normal operation simply by manipulating the bolt 39.

What is claimed is:

1. In a taper attachment for lathes, the combination of a lathe-bed, a lathe-carriage having a cross-slide mounted thereupon, a bracket upon said carriage and having a guide-way, a taper rail having a bracket to support it from the lathe bed, a sliding shoe upon the taper rail, a sleeve slidably mounted in said guide-way, a cross-feed screw connected to the cross-slide and having an end extending through and journaled in said sleeve, and means for connecting 115 said sleeve to said shoe.

2. In a taper attachment for lathes, the combination of a lathe-bed, a lathe carriage having a cross-slide mounted thereupon, a taper rail having a bracket to support it 125 from the lathe bed in a fixed position, a sliding shoe upon the taper rail and adapted to be slid along the rail by movement of the lathe carriage, a long sleeve having one end extending into sliding engagement with 130

the lathe-carriage and the other end slidably supported by a rear bracket upon the lathe-carriage, a cross-feed screw connected to the cross slide and having one end journaled 5 in said sleeve, and means for removably securing said sleeve to the shoe.

3. In a taper attachment for lathes, the combination of a lathe-bed, a lathe-carriage having a cross-slide mounted thereupon, a 10 taper rail having a bracket to support it from the lathe-bed in a fixed position, a sliding shoe upon the taper rail, a long sleeve having one end extending into sliding engagement with the lathe-carriage and 15 having its other end slidably supported by a bracket upon the lathe carriage, a cross-feed screw connected to the cross-slide and having an end journaled in said sleeve, and means to secure said sleeve either to said 20 shoe or in fixed relation to the lathe-carriage.

4. In a taper attachment for lathes, the combination of a lathe-bed, a lathe-carriage having a cross-slide mounted thereupon, a 25 taper rail having a bracket to support it from the lathe bed, a sliding shoe upon the taper rail, a rearwardly extending bracket upon the lathe carriage, a sleeve having sliding engagement with said bracket, a 30 cross-feed screw connected to the cross-slide and rotatably secured to said sleeve, and means for securing the sleeve either to the sliding shoe or rigidly to said bracket.

5. In a taper attachment for lathes, the 35 combination of a lathe-bed, a lathe-carriage having a cross-slide mounted thereupon, a taper rail having a bracket to support it from the lathe bed, a sliding shoe upon the taper rail, a rearwardly extending bracket 40 upon the lathe carriage, a sleeve having sliding engagement with said bracket, a cross-feed screw connected to the cross-slide and having an end journaled in said sleeve, means for securing the sleeve to the sliding 45 shoe, and a bar for rigidly connecting the

cross-slide to the sleeve and constructed to be clamped to the sleeve in different positions of adjustment.

6. In a taper attachment for lathes, the combination of a lathe carriage having a 50 cross-slide mounted thereupon, a rearwardly extending bracket upon the carriage and having a portion in spaced relation to the rear portion of the carriage, a long sleeve having sliding engagement with the spaced 55 portion of the bracket and the carriage and extending across the space therebetween, a cross-feed screw connected to the cross slide and extending rotatably through said sleeve, a taper rail having a shoe slidably mounted 60 thereupon, and means for securing an intermediate portion of the sleeve to the shoe.

7. In a taper attachment for lathes, the combination of a lathe-bed, a lathe-carriage having a cross-slide mounted thereupon, a 65 taper rail having a bracket to support it from the lathe-bed, a sliding shoe upon the taper rail, a long sleeve, means upon the carriage slidably engaging the ends of the sleeve to support it, a cross-feed screw extending through the sleeve and journaled 70 therein and connected to the cross-slide, and means for connecting the sleeve to the sliding shoe.

8. In a taper attachment for lathes, the 75 combination of a lathe-bed, a lathe carriage having a cross-slide mounted thereupon, a taper rail having a bracket to support it from the lathe bed, a shoe slidably mounted upon the taper rail, a cross-feed 80 screw connected to the cross-slide, a sleeve having an end of the cross-feed screw journaled therein, means for supporting the sleeve for sliding movement transversely of the lathe including bearings engaging the 85 ends of the sleeve, and means for securing the sleeve to the shoe.

In testimony whereof, I have signed my name to this specification.

WILLIAM F. GROENE.
